DESIGN FOR A MEASURING SPOON UNIT

Kenneth L. Mathewson, Tacoma, Wash.

Application March 27, 1945, Serial No. 118,732

Term of patent 7 years

(Cl. D52—1)

To all whom it may concern:

Be it known that I, Kenneth L. Mathewson, a citizen of the United States, residing at Tacoma, in the county of Pierce, and State of Washington, have invented a new, original, and ornamental Design for a Measuring Spoon Unit, of which the following is a specification; reference being had to the accompanying drawing, forming a part thereof.

Figure 1 is a top plan view of a measuring spoon unit, showing my new design;

Figure 2 is a side elevational view; and

Figure 3 is a top plan view, showing the measuring spoon unit in spread position.

I claim:

The ornamental design for a measuring spoon unit, as shown.

KENNETH L. MATHEWSON.
